UNITED STATES PATENT OFFICE.

LYMAN R. ROBERTS, OF RUTHERFORD, NEW JERSEY, ASSIGNOR TO UNDERWOOD TYPE-WRITER COMPANY, OF NEW YORK, N. Y., A CORPORATION OF DELAWARE.

PERFORATOR FOR MASTER-SHEETS.

1,177,139.

Specification of Letters Patent. Patented Mar. 28, 1916.

Application filed November 29, 1912. Serial No. 734,048.

To all whom it may concern.

Be it known that I, LYMAN R. ROBERTS, a citizen of the United States, residing in Rutherford, in the county of Bergen and 5 State of New Jersey, have invented certain new and useful Improvements in Perforators for Master-Sheets, of which the following is a specification.

This invention relates to a perforator for 10 preparing master members to be used in connection with automatic typewriter operators, such as that described in my application, Ser. No. 680,586, and is more especially related to a type of machine adapted to perforate cards.

This application is an improvement on the patent to myself and C. L. Davis, No. 953,180, granted March 29, 1910.

It has been found desirable in practice, 20 where it is necessary to keep a number of different names and addresses in a form suitable to reproduce the same when running an automatic typewriter operator, to utilize a series of separate master cards for 25 controlling the automatic typewriter operator.

An object therefore of this invention is to provide an automatic perforator, which by striking the keys of a keyboard some- 30 what similar to the keys of a typewriter, will produce in a blank card apertures corresponding to the operation of the various parts of the typewriter when this perforated card is subsequently run through the 35 automatic operator for the typewriter.

In the embodiment used to illustrate the invention, perforating punches individual to the several keys of a bank of keys are actuated by a common hammer, which is set 40 in motion when any of the keys are actuated, by striking interponents raised by corresponding keys to a position between the hammer and the corresponding punch. The clippings or pieces of cut-out material are 45 caught by a receptacle arranged in such a position that the punches as they act will force the clippings into the receptacle.

The card to be punched is carried preferably by a feeder, which has an automatic 50 step-by-step escapement movement, so as to advance the card a step after each perforation. This escapement mechanism is arranged so that it can be released to enable the card to have a jump movement in case

it is desired to remove the card from the 55 perforator before the limit of capacity for perforations of the same has been reached.

A further object of this invention is to enable an operator to translate the perforations immediately after they are made, so 60 that he can judge whether the same are correct or not. This object is accomplished by placing a lettered index in juxtaposition to the perforating means, and arranging the feeder for the card so that it will feed the 65 card immediately after perforating, to bring the last made perforation right up to the index in alignment with the character indicating the kind of operation which the perforation will produce when the card is subsequently used in an automatic operator for 70 a typewriter.

Other features and advantages will hereinafter appear.

In the accompanying drawings Figure 1 75 is a vertical sectional view from front to rear, showing the parts of the perforator in their inactive position with a card partly fed up as if it had received a number of perforations. Fig. 2 is a detached perspective 80 view of the receptacle for receiving the clippings or cut-out pieces of material from the perforator. Fig. 3 is a detail sectional view of the escapement mechanism for the feeder. Fig. 4 is a detail section of the 85 clutch for connecting the escapement wheel to the feeding shaft. Fig. 5 is a skeleton perspective view showing the relation of the hammer-controlling and actuating mechanism to the card feeder and holder. Fig. 90 6 is a disassembled perspective view of one of the clamps for holding the card in position on the feeder or holder. Fig. 7 is a detail sectional view showing one of the interponents in its raised position ready to be 95 struck by the hammer. Fig. 8 is a view similar to Fig. 7, showing the interponent forced forward by the hammer, so as to force the associated puncher through the card. Fig. 9 is a detached view of the scale which is 100 arranged in juxtaposition to the perforating means, so that the perforations on the master card can be readily translated into the particular type of work, which they are adapted to control. Fig. 10 is a skeleton 105 perspective view of the hammer and the electrical connections to the electromagnets for operating the same. Fig. 11 is a detail

view of the holder, showing a card in position thereon with one of the clamps in its raised or inactive position and the other of the clamps in its depressed or clamping position. Fig. 12 is a detail view of the spring drum which furnishes the motive power for automatically feeding the holder step by step. Fig. 13 is a detail of the escapement mechanism for controlling the 10 step-by-step movement of the feeder. Fig. 14 is a detail sectional view of the clamp and its detent, showing the clamp in its raised or inactive position. Fig. 15 is a view similar to Fig. 14, showing the clamp in its 15 depressed or active position. Fig. 16 is a fragmentary plan view of the machine as a whole with parts broken away to show the underlying structure. Fig. 17 is a detail perspective view of one of the punches used 20 to make a perforation corresponding to a letter or character. Fig. 18 is a perspective view of one of the punches used to produce a perforation corresponding to a movement of the carriage, and in this instance, corresponds to the puncher which produces a 25 perforation corresponding to a tabulating movement of the carriage.

Referring more particularly to the separate parts as embodied in the form shown 30 in the drawings, 1 indicates numeral and character keys which are mounted on key levers 2, pivoted intermediate their ends, as at 3, and engaging at their rear ends with selecting interponents 4, so as to raise the 35 latter to bring heads 5 thereon in opposition to punches 6, slidably mounted in a guide or guiding-block 7. The punches 6 are arranged in opposition to die-openings 8 in a die-block 9, so that when the inter- 40 ponents 4 are raised by their associated keys, a hammer 10 can be actuated to hit the interponents and thus force the punches 6 through the master card 11 being perforated, and mounted so as to pass in a slot 45 12 located between the guide-block 7 and the die-block 9. The clippings or cut-out pieces of material which are thus forced from the body of the card, pass through the die-openings 8 which widen out at their rear, and 50 shoot into a waiting receptacle 13 closed on all but one side where it is provided with an opening 14, which is arranged in opposition to the openings in the die-block 9.

It will be noticed that the floor of the 55 openings in the die-block slopes downwardly, so that the clippings or cut-out pieces of material will naturally gravitate into the waiting receptacle. These openings may also flare upwardly to prevent any 60 clogging of the clippings therein.

The receptacle 13 is preferably so arranged that it can be readily detached and lifted from its receiving position, by a pair of handles 15 on opposite ends thereof, so 65 that the contents can be readily disposed of.

For this purpose, the top of the receptacle projects beyond the body portion, so as to form a pair of overhanging flanges 16, having slots 17 therein. These flanges overlie the die-block 9 to which they are secured by 70 detachable binding screws 18. The punches 6 are retrieved after actuation by levers 120, which are pivoted intermediate their ends and engaged by return springs 121, an extent determined by inwardly-turned lugs 75 122 which engage the guide-block 7.

The hammer 10 is, in this instance, shown to be electrically actuated, and for this purpose is shown in the form of a bell crank lever consisting of an inverted U-shaped 80 striker 19 secured to a shaft 20, on which are also provided a pair of arms 21 having at their ends, armatures 22 arranged to be drawn in contact with cores 23 of a pair of spaced electromagnets 24.

An electric current is caused to flow through the magnets 24 from any suitable source represented by the circuit wires 25, when any of the keys 1 are depressed to bring interponents 4 in between the punches 90 6 and the hammer 10. To accomplish this, there is provided a fixed electrical contact 26 and a moving contact 27 carried by a switch arm 28. The switch arm 28 is mounted on a rock shaft 29, on which is also located a universal frame 30, having a transverse universal bar 31 overlying all of the key-levers 2, at their rear ends, so that when any of these key-levers are actuated the bar 31 will be raised to bring the contact 27 in 100 engagement with the contact 26. When the contacts 26 and 27 are brought in engagement with each other, circuits 32 and 33 will be closed, to connect the electromagnets 24 in parallel in the circuit 25. A condenser 105 34 will also be connected in this circuit between the contacts 26 and 27 to increase the capacity and prevent sparking at the contacts.

When pressure on the actuated key 1 is 110 released, the circuit is broken by having the particular raised key lever, returned to its normal position by the corresponding interponent 4, thereby permitting the bar 31 and other parts on the rock shaft 29 to be returned by gravity and thus separate the contacts 26, 27. The interponent 4 is returned to normal position by a universal return-bar 35, which lies in a series of cut-out channels 36, one of which is provided in each 115 of the interponents 4. The universal return-bar 35 is mounted on arms 37, which are secured to a rock shaft 38, and are normally forced down in a position to hold the bar 35 in its lowermost position, by means of 120 a spring 39, which overlies one of the arms 37 and is coiled about the rock shaft 38.

It will be noted in passing, that the interponents 4 are guided in their vertical movement by a pair of slots 40 and 41, which en- 130

gage bars 42 and 43, respectively, common to all of the interponents. The slot 41 is shown to be vertically extending in contradistinction to the slot 40, which, it will be noted, is in the form of a triangle, with its apex extending upwardly. This is to cause the interponents to assume a certain definite vertical position when depressed, causing them to be rigidly held in this position 10 against transverse movement, but admitting of a swinging movement of the interponents, when they are raised to bring the base of the triangular slot 40 up to the bar 42.

In addition to the normal numeral and character keys 1, there are provided other keys which correspond to various operations of the typewriter. As will be seen by reference to Fig. 16, among these other keys, there is a space-bar key 44, which is secured 15 to arms 45 mounted on a shaft 46 and one of which is engaged by a coil spring 47, so as to normally hold the space-bar key 44 in its raised position. The space-bar key 44 is provided with a projection 48, having a 20 pin 49 overlying a lever-bar 50, similar to the lever-bars 2, and provided with a corresponding interponent, similar to the interponents 4. Other keys which are provided in addition to these keys, are a carriage-return key 51, an upper-case shift-on key 52, an upper-case shift-off key 53 (i. e., a key to shift to lower case), a stop key 54, a control shift key 55, a tabulating key 56, and a 25 card-positioning key 57. All of these specifically-mentioned keys are mounted on key-levers similar to the keys 1, and actuate interponents to be raised to enable the hammer 10 to operate punches like the punch 6, to produce perforations in the master card 30 11.

The punch 6 corresponding to most of the keys, is preferably provided with a reduced portion 58, which is cylindrical to form a circular aperture in the card. One of the punches, however, indicated in Fig. 18, at 35 59, which corresponds to the tabulating key, is so formed that it will, in place of making a circular aperture, produce an aperture elongated in the direction of the feed of the card, so as to afford a longer period of 40 action for tabulating than for other actions, when the card is being used to control the actions of a typewriter. As will be seen by reference to Fig. 18, this formation of 45 the punch is produced by reducing the punch on two sides only, forming a reduced nib considerably thinner than the body of the 50 punch, with flat parallel sides.

Inasmuch as the card being perforated is 55 to be used to control actions of a typewriter, which, for the most part, take place in different successive periods, as, for example, striking character keys successively, it is 60 essential to move the card past the perforating means including the punches 6, after

each perforation has been produced. To this end, the card 11 is mounted in a holder 60, which is shown in the form of an open frame inclosing an opening substantially the shape and size of the card and provided 70 on one or more sides, at least on the bottom side, with grooves 61, to receive the edge of the card (Figs. 1 and 5). The bottom reach of the frame will provide against downward movement of the card and the side reaches 75 of the frame will prevent transverse movement.

The card is inserted in the holder from the top, and in order to prevent upward movement of the card relative to the holder, 80 there are provided on the latter one or more clamps 62, in this instance, two being shown, mounted for movement on a transverse bar 63 connecting the side reaches of the frame and having lugs 64 to prevent a snapping 85 of the middle portion of the card out of the holder. As will be seen by reference to Figs. 1 and 6, each of these clamps is provided with a groove 65 in its bottom edge arranged to be brought in engagement with the top 90 edge of the card, to prevent movement thereof in any direction.

As will be seen by reference to Figs. 6, 14 and 15, the clamp is mounted in each instance, for vertical movement by being 95 provided with a pin 66 extending through a slot 67 in the transverse bar 63. This enables the clamp to play in a guide-way 68, but also permits the clamp to be held in a raised position when not in use, by lugs 69 100 on the clamp engaging ledges 70 on the transverse bar 63 of the holder. The clamp is held in its adjusted position by a detent 71, which engages sockets 72 and 73 for its active and inactive positions, respectively. 105 The detent 71 is loosely mounted by a pin 74, which engages an opening 75 in the transverse bar 63, and is held in locking engagement with the clamp 62 by a spring 76, which encircles the pin 66, and is thus 110 common to the clamp and the detent, so that it serves as a single spring means for the two elements. In order to enable the relative movement between the clamp and the detent, the detent is slotted, as at 77, so 115 that the pin 66 can pass through the same and yet have a movement relative to the detent.

Having described specifically the type of holder which forms a part of the feeder, 120 we now come to the particular feeding means, whereby the holder is advanced step by step to carry the card therein past the perforating means. For this purpose, the vertical reaches of the holder are provided 125 with racks 78, which engage pinions 79 on a motor-driven shaft 80. The shaft 80 is provided with a pinion 81 engaging a gear 82 connected to a motor in the form of a spring drum 83. The initial tension on the 130

spring drum 83 may be adjusted by means of a hand crank 84, and retained by a double 5 detent 85. Complete tension, however, is not generally placed on the drum 83, but the card is inserted in the holder when the latter is in raised position, and the holder is then depressed so that the racks by engaging the gears 79, rotate the shaft 81, to rotate the gear 82, and thus store up potential energy in the spring drum 83. When the spring drum is thus tensioned and the card is in its lowered position ready to receive the initial perforation adjacent to the top edge thereof, the shaft 80 will be locked 10 against rotation by an escapement mechanism indicated in general at 86, which is controlled at the actuation of the keys, to enable a step-by-step movement of the card past the perforating means.

20 The escapement mechanism includes an escapement wheel 87, loosely mounted on the shaft 80 and arranged to be secured thereto by a clutch 88 (Figs. 4 and 5), where it is splined on the shaft 80 and normally held in its active or clutching position by a spring 89, but capable of being moved to its disengaged position by a hand lever 90. The rotation of the escapement wheel 87 is controlled by a fixed pawl 91 and a spring-drawn pivoted pawl 92 mounted on a rock shaft 93. The rock shaft 93 is provided with an arm 94, which is connected by a link 95 to an arm 96 secured to the hammer 10. A spring 97 normally holds the loose or pivoted pawl 92 in engagement with the escapement wheel 87, and aids the weight of the parts in holding the hammer 10 in its inactive position resting against a cushion 98. It will thus be seen that whenever the hammer is actuated, it will rock the shaft 93 to slip the loose pawl 92 out of engagement with the escapement wheel 87, bring the fixed pawl into engagement with this wheel, and permit the loose pawl 92 to snap forward under the tension of a spring, to engage the next succeeding tooth of the escapement wheel, thereby enabling a rotation of the shaft 80 on the return movement of the hammer 10 when the fixed pawl is released from the tooth of the escapement wheel with which it engages. It will be noted in passing, that this feeding movement of the holder, and thus of the card, takes place after the perforation has been made and during the return movement of the hammer and the key which caused the actuation of the same. It will be seen that the movements of the fixed and movable pawls 91 and 92, are limited, respectively, by stops 99 and 100.

65 The use of the release lever 90 for the clutch 88 will now be apparent. In fact, it may be used for two purposes, one of which is to permit the holder with its card to be depressed to starting position without

clicking the escapement wheel 87 past its pawl. Another use to which it may be put, is to enable a jump movement of the holder with its card to a raised position without an actuation of any of the keys, as in case it is desired to remove a spoiled card or in case the card has been finished without using all its available surface. The escapement wheel 87 may be held from accidental movement (see Fig. 3) by means of a detent 101, which engages the teeth of the same.

It may often be desirable to provide for a blank space in the master card 11, that is, to feed the card without perforating it, in case it should be necessary to have perforations corresponding to successive operations at greater than normal distances from each other. To this end, the key-board of the perforator is provided with a blank-space key 102, which is mounted on a lever 103, normally held in a raised position by a spring 104. It will be noted by reference to Fig. 1, that this lever is a short one and does not extend under the universal bar 31, and is not associated with an interponent 4, so that it is incapable of producing a perforation in the master card. It does, however, overlie a pin 105, on an arm 106, which is secured to the rock shaft 29, so that it will swing the switch arm 28 upwardly, to enable an engagement between the contacts 26 and 27, thus completing the circuits through the magnets 24, to produce an actuation of the hammer 10. Inasmuch as no interponent, however, is raised between the hammer and the punches, there will be no perforation produced. Nevertheless, since the hammer is connected to operate the escapement mechanism, this escapement mechanism will be released to permit a step movement of the feeding mechanism, and thus a step movement of the card 11.

It will be apparent by reference to Fig. 1, that the perforations in the master card 11 are produced by the punches 6 at a point which would be at least difficult to see, if not entirely concealed from view. In order that the operator may ascertain whether the proper perforations have been made, so as to make the perforator a visible one, the feeding action, as stated above, takes place immediately after the perforation. This upwardly feeding movement of the card 11 is sufficient to bring the latest-made perforation up to view above the guide-block 7.

In order that the meaning of a perforation, that is, the particular work which it controls, may be readily translated, there is provided an index 107 supported in juxtaposition to the perforating means and to the master card 11 at such a point that the feeding means for the card will bring the latest-made perforation substantially in alignment with the index just after the perforation has been made. This enables the operator to

ascertain the correctness of his work as it is performed.

The particular form of the index may be seen by reference to Fig. 9, wherein it will be apparent that the following characters are found thereon in the named order corresponding to the actuation of like keys of the typewriter: Q A 2 Z W S 3 X E D 4 C R F 5 V T G 6 B Y H 7 N U J 8 M I K 9, 10 O L 0 . P ; — 1 1/2 ¢.

When a capital or upper-case character is to be made, the shift-on key 52 will be depressed first, so as to produce a perforation in advance of the particular aperture corresponding to the upper-case character. This perforation is indicated by the character letters S O (108) in Fig. 9. If but a single upper-case character is written, a change 20 may be made by a depression of the shift-off key 53, to produce a perforation corresponding to the release of the permanent shift key, permitting the carriage to be lowered. This perforation may be translated on the 25 index in Fig. 9, by the character letters S O (109). The index also indicates the character of action of other perforations, as follows:—card-positioner (P); carriage-return (C); tabulating key (T K); control shift (C); stop (S), and space-key (K).

The operation of the device will be readily understood when taken in connection with the above description. The device is started with the holder 60 in its uppermost position when a blank card is inserted therein by 40 passing it through at the top of the holder. The card is then secured in position by shifting the clamps 62 downwardly until the grooves 65 therein engage the top edge of the card. The clamps will be automatically 45 locked in position by the detent 71 engaging in the upper sockets 72. The clutch 88 may then be released to avoid clicking movement of the pawls, and the holder forced down to its lowermost position, so that almost the 50 very top of the card will lie in opposition to the row of punches 6. The keys may then be struck to produce perforations in the card, which will correspond to the desired piece of work which the card will subsequently reproduce when placed in an automatic typewriter operator.

As each of the character keys is actuated, it forces up the associated selecting interponent in apposition to the corresponding punch 6, so that when the contacts 26 and 27 come together on a further movement of the key, the hammer 10 will strike the interponent, to force the punch through the card, the clippings or cut-out pieces of material 65 falling into the waiting receptacle 13.

When the key is released the circuit will be broken and the actuated interponent returned to its normal position. The hammer will likewise return to its position resting on the cushion 98, so that the rigid pawl 91, which was forced into engagement with the escapement wheel during the down stroke of the key and the forward stroke of the hammer, will now be moved out of engagement therewith, and the pivoted spring-pressed pawl 92, which during the down stroke of the key was released to spring forward into engagement with the next escapement tooth, will slip back with the escapement wheel, a distance of one tooth, locking it when this amount of movement has been finished. This permits the shaft 80 to rotate a corresponding amount and permits a single step movement of the holder 60 upward, so that an entirely new blank line is brought in apposition to the row of punches 6. This occurs repeatedly. As each key is pressed it causes the operation of a corresponding punch, which produces a perforation in the card, the latter being fed up automatically after receiving this perforation, a sufficient distance to bring the perforation therein in register with the index 107, so that the operator by merely glancing at the character with which the latest perforation is in alinement, can determine whether the action was correct or not. 95

If a perforation corresponding to any other action than writing a character or letter is desired, such as returning the carriage, 100 positioning a new card, or the like, the corresponding key on the key-board can be actuated with the desired result.

If, for any reason, it should be desired to feed the master card without producing a perforation; it is merely necessary to press the blank-space key 102, which will bring about an engagement of the contacts 26 and 27, to actuate the hammer, and thus release the escapement mechanism without the interposition of a selecting interponent between the hammer and the punches, and, hence, without any perforating action. 110

When the desired subject-matter has been represented on the master card by a series 115 of perforations, the holder can be brought up to its raised position quickly by actuating the lever 90 to release the clutch 88, at which point the card can be readily removed from the holder by releasing the clamps 62. 120 A new card can be placed in position and the operation repeated as often as desired.

Variations may be resorted to within the scope of the invention, and portions of the improvements may be used without others. 125

Having thus described my invention, I claim:

1. The combination with perforating means comprising a die-block having a series of die-openings therein through which 130

the material cut out by the perforating means is ejected, of a receptacle for catching said material, said receptacle abutting the die-block and formed with a single opening, said opening extending along the die-block opposite the die-openings, and closed by the die-block except at the die-openings, and means for detachably securing said receptacle in position, whereby said receptacle can be removed to empty the material through said opening.

2. The combination with perforating means, of a receptacle for receiving the material cut out by said perforating means, said receptacle being closed at the top and bottom and open solely at one side, and said receptacle being removably held in position with its open side abutting said perforating means, so as to readily receive the cut-out pieces of material therefrom.

3. The combination with a perforating means, of a receptacle for receiving the cut-out pieces of material from said perforating means, said receptacle having a flange with slots therein, and binding screws engaging said slots to detachably secure said receptacle in position.

4. The combination with a die-block having a series of openings therein, of a series of punches coöperating with the openings in said die-block, to perforate a master member, a receptacle having an open side abutting against the rear of said die-block, so as to receive the cut-out pieces of material coming through the openings in said die-block, said receptacle having its top projecting over said die-block, and means for removably securing said receptacle in position by engagement with said top.

5. The combination with perforating means, of a receptacle for receiving the cut-out pieces of material from said perforating means, means for detachably securing said receptacle in juxtaposition to said perforating means, and handles extending from opposite ends of said receptacle to enable said receptacle to be lifted from said perforating means.

6. The combination with perforating means, of a card-feeder for moving a master card past said perforating means, said card-feeder comprising an open frame having grooves in the sides thereof to receive the side edges of a card and permitting the card to be slid endwise into said frame, said frame comprising a stop for the leading end edge of the card as it is slid into position in the frame, a clamp shiftably mounted on the frame for movement into and out of position to engage the opposite end edge of the card to thereby detachably secure the card in a fixed position in the frame, and means to automatically lock the clamp in card-holding position.

7. The combination with perforating

means, of a card-feeder for moving a master card past said perforating means, said card-feeder comprising an open frame having grooves in the sides thereof to receive the side edges of a card and permitting the card to be slid endwise into said frame, said frame having an end provided with a groove to receive the leading edge of a card as it is slid into position in the frame, and clamping means mounted on the other end of the frame and provided with a groove for the opposite edge of the card, said clamping means shiftable into and out of position for holding the card in the frame, whereby the card may be held in the frame with all of its edges seated in said grooves.

8. The combination with perforating means, of a card-feeder for moving a card past said perforating means, said card-feeder comprising an open frame having a groove therein along one side to receive one edge of said card, one or more clamps arranged on the opposite side of said card-feeder from said groove and shiftable on the card-feeder into and out of position for holding said card in said groove, and means for automatically locking the clamp or clamps in card-holding position, said clamp or clamps also being grooved to receive the edge of the card opposite said first-mentioned edge, said grooves formed to prevent any material play of the card therein.

9. The combination with perforating means, of a card-feeder for moving a card past said perforating means, said card-feeder provided with parallel grooves forming guideways for opposite edges of a card as it is slid into position on the card-feeder, said card-feeder comprising a stop for the leading edge of the card as it is slid into position thereon, a clamp formed with a groove to engage the opposite edge of the card to secure it in position in the card-feeder, said clamp shiftable from card-holding position into position to release the card and permit its removal from the card-feeder, and means for yieldingly holding the clamp in both positions permitting the clamp to be shifted from either one to the other of said positions by the sole operation of applying a pressure to the clamp in its shifting direction.

10. The combination with card-perforating means, of a card-feeder for supporting a card when moved by said perforating means, said card-feeder comprising an open rectangular frame having grooves in the opposite sides and along one end for engaging the sides and one end edge of a card placed in said frame, and clamps mounted on the opposite end of the frame and formed with the grooves to receive the corresponding edge of the card when the clamps are in clamping position, said clamps shiftable into and out of card-clamping position.

11. The combination with card-perforating means, of a card-feeder for supporting a card when moved by said perforating means, said card-feeder comprising an open 5 rectangular frame having grooves in the opposite sides and along one end for engaging the sides and one end edge of a card placed in said frame, clamps mounted on the opposite end of the frame and formed with the 10 grooves to receive the corresponding edge of the card when the clamps are in clamping position, said clamps shiftable into and out of card-clamping position, and spring-actuated detent means to hold the clamps in 15 both sheet-clamping and sheet-releasing positions.
12. The combination with a holder for supporting a master card to be perforated, of a clamp adjustable to secure said card on 20 said holder, and a detent for holding said clamp in any adjusted position.
13. The combination with a holder for supporting a master card to be perforated, of a clamp for securing said master card in 25 position on said holder, said clamp being adjustable to secure said card, and having a plurality of sockets therein, and a detent capable of engaging any of said sockets to lock said clamp in any adjusted position.
- 30 14. The combination with a holder for supporting a card to be operated upon, of a clamp for securing said card in position on said holder, said clamp being adjustably mounted, a detent for securing said clamp in any adjusted position, and a spring common to said clamp and said detent, for 35 yieldingly resisting the movement thereof.
15. The combination with a holder for supporting a card to be operated upon, said 40 holder being in the form of a frame having a groove on one of its inwardly-facing margins, to receive one edge of said card, and a plurality of clamps adjustably mounted on said holder and having grooves therein, to 45 engage an edge of said card to hold said card against accidental movement.
16. The combination with a holder for supporting a rectangular card to be operated upon, said holder being in the form of a frame arranged to closely engage the edges 50 of said card on three sides thereof, and clamping means for engaging said card on the fourth edge thereof, so as to hold said card against accidental movement in all directions.
- 55 17. The combination with a holder adapted to support a card, of a clamp for securing said card in position on said holder, and a detent for said clamp having a loose pin-and-socket connection with said holder.
18. The combination with perforating means, of a feeder for moving a card past said perforating means, a motor normally tending to actuate said feeder, locking 60 means for preventing the actuation of said 65
- feeder, and releasing means for said locking means.
19. The combination with perforating means, of keys for actuating said perforating means, a card-feeder for moving a card past said perforating means, means normally tending to actuate said card-feeder, and a key-actuated escapement for controlling the movement of said feeder under the impulse of said last-mentioned means. 75
20. The combination with a card-holder, of means to perform work on a card contained in the holder, a rack connected to said card-holder, a gear engaging said rack, a shaft for said gear, an escapement wheel 80 on said shaft, spring means tending to rotate said shaft, and releasable locking means engaging said escapement wheel.
21. The combination with a card-holder, of means to perform work on a card contained in the holder, a rack on said holder, a gear engaging said rack, a motor normally tending to rotate said gear, locking means 85 for preventing the rotation of said gear, and means for releasing said locking means 90 to permit movement of the card holder.
22. The combination with a card-holder, of means to perform work on a card contained in the holder, a rack on said card-holder, a gear engaging said rack, a motor 95 normally tending to rotate said gear, so as to feed said holder, an escapement for controlling the rotation of said gear, and a bank of keys capable of controlling said escapement. 100
23. The combination with perforating means, of a card-holder for supporting a card to be perforated, in juxtaposition to said perforating means, a motor normally tending to feed said card past said perforating means, an escapement for enabling a step-by-step movement of said holder, and means to release the holder from the escapement and enable said holder to move independently of the escapement. 105
24. Means for feeding a master member, including an escapement shaft, an escapement wheel loosely mounted on said shaft, means for controlling the rotation of said escapement wheel, and a clutch splined on 110 said shaft for connecting said escapement wheel to said shaft, said clutch being releasable to permit a rotation of said shaft relative to said escapement wheel.
25. The combination with a card-holder, 115 of means to perform work on a card contained in the holder, a pair of racks on said holder, a pair of gears engaging said racks, a shaft common to said gears, a spring drum for rotating said shaft, an escapement wheel for controlling the movement of said shaft, and pawls engaging said escapement wheel to control the movement thereof. 120
26. The combination with means for perforating a master member at a point con- 125

cealed from view, of means for bringing the perforated part of the master member up to view immediately after perforation.

27. The combination with perforating means for perforating a master member, of an index arranged in juxtaposition to said perforating means and said master member, to enable the translation of the meaning of perforations as they are made in the master member.

28. The combination with perforating means for placing apertures in a master member, of an index arranged in juxtaposition to said perforating means, and having characters thereon corresponding to the various perforations and indicating the character of work which each perforation is to control, and feeding means for bringing each perforation after having been made, into register with said index, so that the character of each perforation can be readily ascertained.

29. The combination with means for altering the general uniform character of a master member at successive points corresponding to the various different operations to be controlled by the master member, of an index arranged in juxtaposition to said master member, and having characters thereon designating the particular action controlled by each of said points where the uniform character of the master member is altered, whereby the meaning of the master member can be readily translated and read off by reference to said index.

30. The combination with means for altering the general uniform character of a master member at successive points corresponding to the various different operations to be controlled by the master member, of an index arranged in juxtaposition to said master member, and having characters thereon designating the particular action controlled by each of said points where the uniform character of the master member is altered, whereby the meaning of the master member can be readily translated and read off by reference to said index, and feeding means for bringing each point just after it has been altered into register with said index.

31. The combination with perforating mechanism, of keys for controlling the action of said perforating mechanism, feeding means for a master member to be perforated, an index having characters to designate the meaning of the various perforations in said master member, and an escapement for said feeding means, controlled from said keys, so as to enable a feeding movement of said feeding means solely after each perforating action of said perforating means incited by said keys.

32. The combination with perforating means, of feeding means for moving a mas-

ter member to be perforated past said perforating means, an escapement for said feeding means, and keys for controlling the action of said perforating means and said escapement, said escapement permitting a feeding movement of said feeding means solely during the return stroke of said keys.

33. The combination with a series of punches, of a series of keys corresponding to said punches, a hammer common to all of said punches and to all of said keys, a series of interponents individual each to a corresponding key and to a corresponding punch, said interponents being movable by said keys between said punches and said hammer, and a cushion for supporting said hammer in its silent position.

34. The combination with a guide, of a punch mounted for movement in said guide, a power device to actuate the punch, said power device being normally free from the punch, a lever engaging said punch and operated directly thereby during the actuation of the punch by the power device, and a spring engaging said lever to retrieve said punch when the power device is withdrawn after actuating the punch.

35. The combination with a guide, of a punch mounted for a straight line bodily movement in said guide, a power device normally free from the punch and arranged to strike the punch to effect said movement thereof, a lever loosely engaging said punch and operated directly by the punch during said movement of the punch, and a spring engaging said lever to retrieve said punch, said lever having a lug to limit the return movement of said punch.

36. The combination with perforating means, of a feeder for carrying a master card past said perforating means, an escapement for said feeder, including an escapement wheel, a pair of alternately-acting pawls for enabling a step-by-step movement of said feeder, and a detent for preventing the accidental return movement of said feeder.

37. The combination with a plurality of punches, of keys corresponding to said punches, a series of interponents corresponding to said keys and to said punches, a guide rod for said interponents, and a hammer common to all of said keys and all of said interponents, said interponents being connected to be shifted between said punches and said hammer at the actuation of the corresponding key, each of said interponents having a triangular slot to engage said guide rod, so as to permit a swinging movement of said interponents in their interposed position, and so as to prevent accidental oscillation in their retired position.

38. The combination with a series of punches, of a holder for supporting a mas-

ter member in juxtaposition to said punches, an escapement for controlling the movement of said holder, a hammer for actuating said punches, and means for controlling said escapement from said hammer.

39. The combination with a key-board having keys with levers arranged in a predetermined order from left to right, of automatic mechanism controlled by said key-board for altering the general uniform character of a blank member at a plurality of distinct points, to enable the member to act subsequently as a master member in controlling the operation of a certain other machine or device, and a characterized index arranged in juxtaposition to said member, so that the altered points therein may come in register with the characters on said index.

40. The combination with a key-board having keys with levers arranged in a predetermined order from left to right, of automatic mechanism controlled by said key-board for altering the general uniform character of a blank member at a plurality of distinct points, to enable the member to act subsequently as a master member in controlling the operation of a certain other machine or device, and an alphabetical index arranged in juxtaposition to said member, so that the altered points therein may come in register with the characters on said index, said index having the following characters arranged in the named relation: Q A 35 2 Z W S 3 X E D 4 C R F 5 V T G 6 B Y H 7 N U J 8 M I K 9 , O L 0. P.

41. The combination with a key-board having keys with levers arranged in a predetermined order from left to right, of automatic mechanism controlled by said key-board for altering the general uniform character of a blank member at a plurality of distinct points, to enable the member to act subsequently as a master member in controlling the operation of a certain other machine or device, and an alphabetical index arranged in juxtaposition to said member, so that the altered points therein may come in register with the characters on said index, the characters on said index corresponding to the character keys of said key-board being arranged on said index in the same order from left to right as the associated levers for said keys are arranged.

42. The combination with a key-board having keys with levers arranged in a predetermined order from left to right, of automatic mechanism controlled by said key-board for altering the general uniform character of a blank member at a plurality of distinct points, to enable the member to act subsequently as a master member in controlling the operation of a certain other machine or device, and an alphabetical index arranged in juxtaposition to said member, so

that the altered points therein may come in register with the characters on said index, the characters on said index corresponding to the character keys of said key-board being arranged on said index in the same order 70 from left to right as the associated levers for said keys are arranged, said index also having other characters corresponding to other keys of said key-board which produce altered points corresponding to the control 75 of the actuation of various parts of an automatic typewriter operator.

43. The combination with a tabulating key, of a punch for producing an aperture in a master member, and connecting mechanism 80 enabling said tabulating key to actuate said punch, said punch having an elongated perforating end arranged to produce an elongated aperture in said master member, whereby when said master member is subsequently used to control the action of an automatic machine, the action controlled by said particular aperture will be, in effect, an appreciable period of time.

44. The combination with perforating 90 means, of keys for controlling the action of said perforating means, connecting mechanism between said keys and said perforating means, said perforating means including a punch having a reduced nib of greater magnitude in one transverse direction than in another, and having faces parallel with its axis of greatest magnitude.

45. The combination with a series of keys, of perforating means controlled by said 100 keys, a universal bar common to all of said keys, enabling the actuation of said perforating means, a blank-space key falling short of said universal bar, and means for enabling said blank-space key to actuate certain parts of said perforating means 105 effectively.

46. The combination with an electric circuit, of a series of keys, a bar universal to many of said keys for closing said circuit, 110 means individual to certain of said keys for closing said circuit, punches individual to certain of said keys, and means controlled by said circuit for actuating the punches.

47. A master member perforator including key-controlled means for producing a feeding step movement of said master member with the perforating of said master member, key-controlled means for producing solely a feeding step movement of said 115 master member, and means for producing any desired major movement of said master member.

48. The combination with punching mechanism comprising a die-block with a die-opening therethrough, of a receptacle to receive punchings ejected through said opening, said receptacle being closed at its top, bottom and ends, and open solely at one vertical side thereof, said die-block having a 125 130

vertical face against which the open side of the receptacle abuts with the die-opening opposite the opening in the receptacle, and a clamp to detachably secure the receptacle to the die-block.

49. The combination with a series of perforating devices, of a hammer for actuating said devices, keys individual to said devices, means actuated by said keys to effect an operative relation between the hammer and the perforating device corresponding to the actuated key, means also controlled by the keys to cause the actuation of the hammer when any key is operated, work-feeding means controlled by said hammer, and means to produce an action of the hammer without operating any of the perforating devices, whereby the work may be fed without the operation of the perforating devices.
50. The combination with perforating means, of a card-holder, a spring motor, and feeding means actuated by the motor for moving said holder with a card therein past said perforating means, and operable to rewind the motor when the card-holder is returned.

51. The combination with a card-holder, of means to perform work on a card contained in the holder, a spring drum, and means actuated by the spring drum for feeding said card-holder, said second means forming a driving connection between the card-holder and drum for rewinding the drum.

52. The combination with a card-holder, of means to perform work on a card contained in the holder, means for feeding said card-holder, a spring drum for actuating said feeding means, said second means being operable to rewind the drum when the card-holder is returned, and means for adjusting the tension on said spring drum.

53. The combination with perforating means, of a feeder for moving a card past said perforating means, means normally tending to actuate said feeder, escapement mechanism controlling the actuation of said feeder, and means to release the feeder and permit it to move independently of the escapement mechanism.

54. The combination with a card holder, of means to perform work on a card contained in the holder, a rack on the card holder, a motor to move the holder, a pinion in mesh with said rack, a shaft carrying said pinion, and an escapement device controlling the rotation of said shaft.

55. The combination of a card-holder in the form of an open rectangular frame to engage the edges only of a card, said frame being formed with grooves on the inner faces of opposite sides and one end thereof, to permit the card to be slid endwise into the frame to a position in which the sides and one end of the card are seated in said

grooves, card-locking means mounted on the other end of the frame and shiftable thereon into and out of position to engage the corresponding end of the card and lock it in the frame, and means to perform work on the card while locked in the frame.

56. The combination of a card-holder in the form of an open rectangular frame to engage the edges only of a card, said frame being formed with grooves on the inner faces of opposite sides and one end thereof, to permit the card to be slid endwise into the frame to a position in which the sides and one end of the card are seated in said grooves, a clamp formed with a groove to receive the opposite end of the card, said clamp shiftable into and out of card-holding position in which the groove therein registers with said first-mentioned grooves, and means to perform work on the card while in position on the holder.

57. The combination of a card-holder in the form of a rectangular open frame, a grooved clamp attached to one side member of the frame and movable thereon into and out of position to bring the edge of a card within said groove, means to automatically lock the clamp in card-holding position, the opposite side member of said frame having a groove to receive the opposite edge of the card, and means to perform work on the card in the holder.

58. The combination of a card-holder, means to feed it vertically, a swinging hammer, punches, and means for effecting an operative relation between the punches and the hammer and cause the punches to be actuated by said hammer and perforate a card on the holder.

59. The combination with card-perforating mechanism, of a card-holder, a rack connected to said card-holder, a gear engaging said rack, a shaft for said gear, an escapement wheel on said shaft, spring means tending to rotate said shaft, and locking means engaging said escapement wheel, and releasable to permit the card-holder to be moved relatively to the perforating mechanism.

60. The combination with card-perforating mechanism, of a card-holder, a rack on said holder, a gear engaging said rack, means normally tending to rotate said gear, locking means for preventing the rotation of said gear, and means for releasing said locking means to permit movement of the card-holder.

61. The combination with card-perforating mechanism, of a card-holder, a rack on said card-holder, a gear engaging said rack, means normally tending to rotate said gear so as to feed said holder, an escapement for controlling the rotation of said gear, and a bank of keys capable of controlling said perforating mechanism and escapement.

62. The combination with card-perforat-

ing mechanism, of a card-holder, a pair of racks on said holder, a pair of gears engaging said racks, a shaft common to said gears, a spring drum for rotating said shaft, an escapement wheel for controlling the movement of said shaft, pawls engaging said escapement wheel to control the movement thereof, and means for operating said pawls when the perforating mechanism is operated 10 and thereby effecting a feeding movement of the card-holder.

63. The combination with card-perforating mechanism, of a card-holder, a spring drum, and means actuated by the spring 15 drum for feeding said card-holder, said means forming a driving connection between the card-holder and drum for rewinding the drum.

64. The combination with card-perforating mechanism, of a card-holder, means for feeding said card-holder, a spring drum for actuating said feeding means, said means being operable to rewind the drum when the 20 card-holder is returned, and means for adjusting the tension on said spring drum.

65. The combination with card-perforating mechanism, of a card-holder, a rack thereon, a motor to move the holder, a pinion in mesh with said rack, a shaft carrying 25 said pinion, an escapement device controlling the rotation of said shaft, and keys for effecting the operation of the perforating mechanism and escapement device.

66. In a perforating machine, the combination of card-perforating mechanism, a card-holder in the form of an open rectangular frame to engage the edges only of a card, the opposite sides of the frame being shaped on the inner faces thereof to form 30 guideways permitting the card to be slid into position on the frame by an endwise movement of the card, one end of the frame forming a stop for the leading edge of the card as it is slid into position, the opposite 40 end of the frame being offset with respect to said guideways to permit the card to be slid into position, and card-holding means on said last-mentioned end of the frame shiftable into position to engage the end 45 of the card, and thereby secure it in 50 position on the frame.

67. In a perforating machine, the combination of card-perforating mechanism, a card-holder in the form of an open rectangular frame to engage the edges only of a card, the opposite sides of the frame being shaped on the inner faces thereof to form 55 guideways permitting the card to be slid into position on the frame by an endwise movement of the card, one end of the frame forming a stop for the leading edge of the card as it is slid into position; the opposite 60 end of the frame being offset with respect to said guideways to permit the card to be slid into position, and card-holding means 65

on said last-mentioned end of the frame shiftable into position to engage the end edge of the card, and thereby secure it in position on the frame, said holding means formed with a groove in which the end of 70 the card is seated when the holding means is in operative position, the opposite end of the frame also being provided with a groove to receive the corresponding end of the card, whereby the card is held at each of its edges 75 against any material play or movement in any direction.

68. The combination with card-perforating mechanism, of a card-holder in the form of a rectangular open frame formed with 80 grooves along the inner faces of opposite sides and one end of the frame, permitting a card to be slid endwise into the frame with its side edges and end edge seated in said grooves, the opposite end of said frame being offset with respect to said grooves to permit the card to be slid into position, a clamp mounted on said last-mentioned frame end and formed with a groove to receive the corresponding end of the card, said clamp 85 guided to shift from a position at one side of the path of the card as the latter is slid into the frame, to a position in which the groove in the clamp receives the edge of the card, and spring-detent means to hold the 90 clamp in both positions.

69. The combination of a frame to carry work, means for advancing the frame step by step to space the work, alphabet keys, work-performing means controlled by said 100 keys, and a stationary support for the work opposite said work-performing means.

70. The combination of an upstanding frame, alphabet keys, a work-performing contrivance at the front of said frame and controlled by said keys, a stationary work-support at the rear of said frame, and means for raising said frame relatively to said 105 work-support to space the work.

71. The combination of an upstanding frame having means to hold a card on edge in a flat condition, means to guide said frame up and down in a straight line, a work-performing contrivance for engaging the front of a card held in said frame, a 110 stationary work-support to engage the rear face of the card, and means for adjusting said frame to vary the point at which work is performed thereon.

72. The combination of a frame to carry 115 work, a row of punches arranged to be on one side of the work, matrices arranged to be on the opposite side of the work, alphabet keys to control said punches, and means for effecting step-by-step movements of said 120 frame to space the work.

73. The combination of a frame to carry work, alphabet keys, work-performing means controlled by said keys and arranged 125 on one side of said frame, a stationary sup- 130

- port for the work on the other side of said frame, a rack on said frame, a pinion to engage said rack, and means to operate said pinion to space the work.
- 5 74. The combination of an upstanding frame constructed to carry a card or work-piece in flat condition, means for driving said frame up and down, alphabet keys, a series of work-performing devices controlled by said keys to operate upon the front of the work, a fixed support arranged to present a flat supporting surface in rear of the work for supporting the work when operated upon, and means for effecting step-by-step movements of said frame to space the work.
- 10 75. The combination with a frame to carry a work-sheet or card, of punching mechanism comprising a series of punches located on one side of the card or work-sheet when the latter is in said frame, keys to operate the punches, a stationary support for the work-sheet or card on the opposite side thereof from said punches to support the work-sheet or card when the punches are operated, and means controlled by the keys to impart a step-by-step movement of the frame to advance the work-sheet or card.
- 15 76. The combination with a frame to carry a work-piece of sheet material, of punching mechanism comprising a series of punches located on one side of the work-piece when the latter is in said frame, a stationary support for the work-piece on the opposite side thereof from said punches to support the work-piece when the punches are operated, alphabet keys to operate said punches, and means controlled by said keys to impart a step-by-step movement to the frame to advance the work-piece.
- 20 77. The combination with a frame to support a work-sheet or card in a flat condition, of devices on one side of the sheet or card, to perform work thereon, a stationary support on the opposite side to support the work-sheet or card when said devices are operated, and step-by-step mechanism to automatically advance the work-sheet or card in its own plane step-by-step as said devices are operated, to thereby space the work.
- 25 78. The combination of a rectangular open frame having means to engage the edges of a card or sheet and hold the same in flat condition in the frame, means for altering the general uniform character of the said sheet or card comprising devices to act on the sheet or card and located on one side of the sheet or card, means to operate said devices, a support for the sheet or card on the side opposite said devices for supporting a card when said devices operate, and step-by-step feeding mechanism controlled by said operating means for moving said frame to feed the sheet or card forward over the stationary support after each operation of said devices.
- 30 79. The combination of a rectangular open frame having means to engage the edges of a card or other work-piece of sheet material, and hold the same in flat condition in the frame, means for altering the general uniform character of the said work-piece comprising operating devices located on one side of the work-piece, a support for the latter on the side opposite said operating devices for supporting the work-piece when said devices operate, a set of keys for selectively operating said devices, a motor, and mechanism controlled by said keys to cause the motor to impart a step-by-step movement of the frame in a direction to advance the work-piece.
- 35 80. The combination of a frame arranged to hold a card in an upright flat condition, punches arranged in a transverse row on one side of the card, a stationary support on the opposite side of the card and in juxtaposition to the punches, to support the card when the punches are actuated, a keyboard comprising keys to selectively operate the punches and thereby perforate the card at points whose lateral positions are determined by the selected keys, means controlled by said keys to advance the frame each time a key is actuated, and means to guide the frame in a direction to move the card forward in its own plane when the keys are operated.
- 40 81. The combination with a frame to carry a card or work-sheet, of a row of punches arranged to extend along one side of the card, a die block positioned to extend along the opposite side of the card and provided with die openings to receive the operated punches, keys to operate the punches, and means operated by the keys to impart a step-by-step movement of the said frame to feed the card forward in a direction perpendicular to the row of punches.
- 45 82. The combination of a frame constructed to carry a card or work-piece in flat condition, alphabet keys, work-performing means controlled by said keys and arranged on one side of the work-piece in the frame, a stationary support for the work-piece on the side opposite said work-performing means, a rack on the frame, a pinion to engage said rack, means to drive said frame to advance the work-piece, and escapement mechanism operated by said keys to control the rotation of said pinion and thereby permit a step-by-step advance of the work-piece as the keys are actuated.
- 50 83. The combination with perforating devices and means to selectively actuate said devices, of feeding means for moving a card or sheet past said perforating devices, escapement mechanism operated by said actu-

ating means and controlling said feeding means to effect a step-by-step movement of the card, and a stationary support on the opposite side of the card from said perforating devices to support the card when said devices are operated.

84. The combination with perforating means, of a feeder for moving a card or sheet past said perforating means, a stationary support on the opposite side of the card from said perforating means to support the card when said means is operated, keys to selectively operate said perforating means, and escapement mechanism to control the operation of said feeder, and thereby effect a step-by-step advance of the card as the keys are actuated.

85. The combination with a series of punches, of a guiding block in which the punches are mounted, a die block formed with die openings to receive the ends of the punches as the latter are operated, said guiding block and die block being spaced to form a slot or narrow opening through which a card or other work-sheet may be guided, a frame to support a card extending through said slot, and means to operate the punches.

30 86. The combination with a series of punches, of a guiding block in which the punches are mounted, a die block formed with die openings to receive the ends of the punches as the latter are operated, said guiding block and die block being spaced to form a slot or narrow opening through which a card or other work-sheet may be guided, a frame to support a card extending through said slot, keys provided with designating characters and arranged to selectively operate the punches corresponding to the selected characters, and thereby perforate the card or work-sheet at points corresponding to the selected character, and means controlled by the keys to carry said frame forward when the keys are operated and thereby feed the card or work-sheet through said slot.

35

40

45

50 87. The combination with an upright frame comprising means to support a work-piece in an upright, flat condition thereon, of a set of character keys, devices to strike rearwardly at the front face of the work-piece and individually controlled by said keys for producing impressions on the work-piece corresponding to the actuated keys, and means also controlled by the keys for

effecting a step-by-step upward movement 55 of said frame to feed the work-piece.

88. The combination with an upright frame comprising means to support a work-piece in an upright, flat condition thereon, of a set of character keys, devices to strike rearwardly at the front face of the work-piece and individually controlled by said keys for producing impressions on the work-piece corresponding to the actuated keys, a motor to move said frame upwardly for feeding the work, and escapement mechanism controlled by the keys to control said movement of the frame, whereby a step-by-step movement of the frame is effected as the keys are actuated. 70

89. The combination with an upright frame comprising means to support a work-piece in an upright, flat condition thereon, of a set of character keys, devices to strike rearwardly at the front face of the work-piece and individually controlled by said keys for producing impressions on the work-piece corresponding to the actuated keys, upright racks on said frame, a drive shaft, pinions thereon running in mesh with said racks for raising the frame, means to drive said shaft, and escapement mechanism controlling the rotation of said shaft and controlled by the keys for causing a step-by-step movement of the frame to feed the work-piece. 70 75 80 85

90. The combination of an upright frame having means to support a work-piece in an upright position, said frame mounted to move up and down, a series of impression-producing devices arranged to strike at the front face of the work-piece, said devices having individual striking points, each at a different position transversely of the work-piece, said points arranged in a horizontal row, keys to individually actuate said striking devices, and means controlled by the keys to impart a step-by-step upward movement to said frame, whereby at each operation of an impression-producing device, the work-piece is advanced a step in a vertical direction, to bring a blank portion thereof into position to receive the next impression. 95 90 100
